COLLAPSIBLE EGG CASE

Robert M. Fenton, Mansfield, Ohio

Application October 21, 1938, Serial No. 236,289

1 Claim. (Cl. 220—7)

My invention relates to an improved construction of collapsible cases or shipping containers particularly adapted for eggs.

An object of my invention is to provide a collapsible case of relatively light and inexpensive construction which may be set up or collapsed quickly and easily; said case when set up being preferably of dimensions equal to standard egg cases of the central partition type.

10 A further object of my invention is the provision of a collapsible egg case, preferably made an egg case having hingedly mounted side walls and hingedly mounted end walls and center partition, all of which are adapted to be pivoted into 15 overlapping adjacent position within the bottom tray portion.

15 A further object of my invention is the provision of a collapsible egg case, preferably made of light and inexpensive sheet metal having end 20 and side walls and central partition hingedly mounted with respect to the relatively shallow bottom tray portion, and having a novel and special top or cover adapted to be folded inwardly in adjacent position with the pivoted and overlapped side and end walls, one of the longitudinal 25 side walls forming the top of the collapsed case to thereby form a relatively compact space-saving package.

20 A further object of my invention is the provision of a collapsible egg case having the above 30 mentioned novel features, in combination with yieldable, releasable fastening elements at various points thereon whereby the case may be quickly and easily set up or disassembled and secured in 35 collapsed position.

Other and further objects of the invention will be apparent from the drawings and from the detailed description which follows.

On the drawings:

40 Fig. 1 is a perspective view with parts broken away showing my collapsible case in partially collapsed position.

Fig. 2 is a cross sectional view taken across the width of the case and showing relative positions 45 of the foldable parts when case is in collapsed position.

Fig. 3 is an enlarged cross sectional view of one of the corners of the box illustrating details of the hinge elements.

50 Fig. 4 is a vertical cross sectional view through a central longitudinal plane and showing parts broken away.

Fig. 5 is a transverse cross sectional view through the set up and closed case.

55 Fig. 6 is an enlarged and elevational view of

central partition and bracket holding means therefor.

Fig. 7 is an enlarged fragmentary view of the releasable fastening elements at the corners of the case.

Fig. 8 is an enlarged fragmentary view of one of the releasable interlocking fastening elements whereby the top of the case is secured in position.

Referring to the drawings, reference numeral 10 designates the flat bottom of the box-like lower 10 or tray-like portion of the collapsible case of my invention. Opposite parallel longitudinal side walls 11 and end walls 12 are formed preferably integral with bottom 10, the side and end walls being of relatively short height and extending 15 perpendicularly. Spaced apart hinge knuckles 11a are formed integral and along the upper edge of each of the side walls 11 and similar hinge knuckles 12a are formed along the upper edges of end walls 12.

20 Said hinge knuckles 11a are made to interfit and cooperate with hinge knuckles formed on the lower edges of hinged or pivoted longitudinal side walls 13 and 14 and said interfitting hinge knuckles are adapted to receive a suitable rod or 25 pintle 15. Cooperating and interfitting knuckles 16a are formed on the lower edges respectively of hinged and collapsible side walls 16 and 17 and said end panels are hingedly mounted by end 30 pintles 18.

As illustrated in Figs. 1 and 2, the respective hinged side wall panels and end wall panels pivot into or upon the tray-portion defined by lower side and end walls 11 and 12, the end panels being preferably laid inward before the hinged 35 side walls 13 and 14.

The portion which comprises the top of the set-up egg case is composed of two substantially rectangular panel sections 19 and 20, which have interfitting hinge knuckles formed along their 40 adjacent longitudinal edges and which are pivotally connected together by said knuckles and by a suitable pintle 20a. Panel section 19 is relatively narrow and panel section 20 is of such a width that the combined area of panels 19 and 20 45 will form a complete top or cover for the top of a set-up case.

One longitudinal edge of panel section 19 is hingedly connected to the adjacent edge of side wall panel 13 by interfitting cooperating hinge 50 knuckles formed respectively on said adjacent edges, and by a suitable pintle 21.

The central partition or panel of the egg case comprises the rectangular panel 22 which is of a size to reach the top when the egg case is set 55

up, as illustrated in Fig. 5. The lower edge of panel 22 is turned to form a knuckle and is pivoted on the central portion of a bail-like off-set rod 23 whose outwardly extending angular feet are 5 stationarily secured upon the bottom 10 by metal brackets 24 respectively, said metal brackets being preferably riveted to said bottom, as illustrated in Fig. 6, or otherwise suitably secured thereto as by welding. Said bail-like rod 23 is secured so 10 that it remains in a plane perpendicular to bottom 10.

In order that the collapsible egg case be easily, quickly and rigidly set up into usable form in the packing process, I provide releasable fastening means for quickly securing the walls of the case in "set-up" position. Such means includes 15 four cooperating interlocking fasteners, one at each interior corner and each comprising an angular bracket arm 25 having a base 25a riveted 20 to the end walls 16 and 17 respectively, as illustrated in Fig. 7. The bracket is formed by bending the extending projecting portion along a diagonal line, as illustrated in Fig. 7, to cause the end 25b to project downwardly toward the bottom of the case. Each of the downwardly projecting ends 25b are stamped to form outwardly extending rib 25c.

The fastening elements which cooperate with the afore-described angular brackets each 30 consists of a metal plate preferably made from spring steel and designated by reference numeral 26, as illustrated in Fig. 7. Each of the metal clips comprises the apertured base portion by means of which said clips are secured by rivets or the like, 35 upon each of the opposite pivotal side walls and at opposite ends thereof, as illustrated in Figs. 4, 5 and 7, the same being in a position to engage and receive the extending ends 25b of bracket arms 25 respectively.

40 The free portions of each of the clips 26 are bent and off-set away from the wall panel on which they are mounted and are bent to form an inwardly opening recess 26a which is adapted to receive the projecting rim 25c of the bracket 25 with which it cooperates. The extreme free end 45 of the clips 26 is bent outwardly so that the end wall panel, when pivoted, may be snapped into position and so that said bracket and clip interengage, as illustrated in Fig. 7.

50 After the vertical side walls and end walls have been set-up into vertical position, the shipping case is ready to be packed with its contents, and after being packed, the top which comprises the two hinged-together rectangular panels 19 and 55 20 will be pivoted into a position to form a cover, and secured in such covering or locked position by suitable fastening means such as illustrated in Figs. 1 and 8. Said illustrated fastening means comprises a pair of spaced apart integral extensions 27 formed on the free edge of the panel 20, and each of said extensions having a slot 27a 60 therein.

Formed on the upper edge of the pivotal side wall 14 and in positions to cooperate with the 65 slotted extensions 27, are a pair of yieldable spring clips 28, each of which is secured at its lower end by welding or the like to the upper edge of the pivotal wall panel 14. Each of said yieldable spring clips 28 comprises a pair of opposed metal sections which are spaced apart and 70 separated at their upper ends to present a pair of rounded surfaces on opposite sides thereof. As

the normal position of the spaced apart springable sections of spring clips 28 is greater than the width of each of the slots 27a with which they cooperate, said upper separated sections will be pressed together when the top is closed and 5 the extension 27 pressed downward thereon to cause said spring clips 28 to snap into the respective slots 27a. When it is desired to open said top, it is merely necessary to firmly pull upwardly on the metal extensions 27 to cause contraction 10 of said clips 28 and a consequent separation of said top from said securing means.

It will be apparent from the foregoing description and the accompanying drawings, that my invention provides a collapsible shipping case for 15 eggs or other merchandise of relatively light though strong and inexpensive construction, and which when desired to be shipped back to the source of supply of the goods, may be quickly and easily collapsed and secured into a compact 20 package for convenient handling and inexpensive shipment.

Various changes may be made in the embodiment of the invention herein specifically described without departing from or sacrificing any of the 25 advantages of the invention or any features thereof, and nothing herein shall be construed as limitations upon the invention, its concept or structural embodiment as to the whole or any part thereof except as defined in the appended 30 claim.

I claim:

A collapsible egg case comprising a bottom tray-like portion consisting of a bottom and integral relatively shallow vertical side and end 35 walls, said side and end walls being joined at the corners thereof respectively; hinge knuckles on the upper edges of said side and end walls; a pair of end wall panels pivotally mounted along the lower edge of each thereof to the hinge 40 knuckles of the shallow end walls of said tray-like section; a pair of longitudinal side walls hingedly connected to the upper edges and knuckles respectively of said shallow tray-section side walls; releasable fastening elements on said 45 pivotal side walls each thereof including a downwardly projecting arm; spring clips on said end walls respectively and positioned at the corners respectively whereby said arms of said side wall fastening elements are releasably secured in vertical set-up position; a pair of substantially rectangular top panels pivotally connected together along their adjacent longitudinal edges, one of said top panels being of substantially smaller area than the other, said smaller top panel being 50 hingedly connected to the edge of one of the pivotal side walls of said case, one of said top panels being adapted to be folded inwardly when said case is collapsed; a transverse partition panel adapted to be maintained across the center of 55 said tray-section to form two compartments; a metal bail pivoted at its ends to the bottom of the case, said transverse partition being connected at its lower end to said bail; interfitting fastening elements on the free edge of the outer 60 of said top panels; cooperating fastening elements on the upper edge of said pivotal side wall whereby said top panels may be releasably secured in closed position; and spring clip retaining members on the tray end walls adapted to 65 hold said case in collapsed position.

ROBERT M. FENTON.
